UNITED STATES PATENT OFFICE.

FREDERICK C. KROEGER, OF ANDERSON, INDIANA, ASSIGNOR TO GENERAL MOTORS CORPORATION, A CORPORATION OF DELAWARE.

IGNITION APPARATUS.

Application filed November 20, 1923. Serial No. 675,945.

To all whom it may concern:

Be it known that I, FREDERICK C. KROEGER, a citizen of the United States of America, residing at Anderson, county of Madison, State of Indiana, have invented certain new and useful Improvements in Ignition Apparatus, of which the following is a full, clear, and exact description.

This invention relates to cam operated periodic circuit breakers, such as ignition timers for internal-combustion engines, and has among its objects to simplify the construction of such apparatus in order to reduce the cost of manufacture. In order to obtain this object, the invention consists in providing strips of non-conducting material of the desired sectional contour and dimensions, so constructed that rubbing blocks or cam followers can be readily formed simply by cutting off sections of the strip of non-conducting material.

Further objects and advantages of the present invention will be apparent from the following description, reference being had to the accompanying drawings, wherein a preferred embodiment of one form of the present invention is clearly shown.

In the drawings:

Figs. 1 and 2 are sectional and fragmentary plan views, respectively, of a strip of material from which the cam followers or rubbing blocks for a periodic circuit breaker can be constructed.

Fig. 3 is a plan view of a circuit breaker or timer provided with a rubbing block made from material shown in Figs. 1 and 2.

Referring to Figs. 1 and 2, the strip of material 20 from which rubbing blocks may be constructed, is formed from layers of cloth 21 and a non-conducting material such as bakelite which can be formed or molded into a permanent shape. The strip of material is angular or L-shaped in cross-section; and rubbing blocks 23 cut from the strip 20, along a line such as 22 at right angles to the length of the strip, will have legs 24 and 25. The layers of cloth in one leg 24 are continuous with the layers of cloth in the leg 25. Each cloth layer 21 includes a substantially straight portion 26 in the leg 24, and a straight portion 27 in the leg 25. The portions 26 and 27 are joined by a curved portion 28, which, as regards the innermost layer of cloth, is rela-

tively gradual in curvature in order that the 55 cloth fibers will not be broken. This formation of the cloth layers is obtained by bending them over a suitably curved surface in the mold in which the layers are molded with the non-conducting material. The portion 29 of the rubbing block material, which does not include cloth, is composed of the hardened non-conducting material, such as bakelite.

The cloth layers 21 are of finely woven 65 material of thread having considerable strength. Fine muslin or linen are preferable. The cloth is arranged so that the warp threads 30 extend substantially at right angles to the long dimensions of the 70 strip 20. This arrangement is preferable because the number of warp threads generally exceed the number of weft threads in a piece of goods. The warp threads 30 extend, therefore, parallel to the legs of the 75 rubbing block 23, and materially resist bending stresses at the apex of the block. The warp threads end in the end faces of the legs 24 and 25 as indicated by the dots 30^a in Fig. 2. Therefore, the greater number 80 of warp threads, the greater will be the resistance to wear offered by these end faces.

As an example of a use to which such rubbing block material is susceptible, a periodic circuit breaker or ignition timer is 85 shown in Fig. 3 of the drawings. Support 31 carries a stud 32 providing a pivotal mounting for a hub 33 to which one end of the strip of material, channel-shaped in section, is attached to provide a breaker lever 90 34. Lever 34 supports a movable contact 35 engaging a stationary contact 36 attached to an adjusting screw 37 threaded into a bracket 38 supported by the plate 31 but insulated therefrom. One leg, such as 25, of 95 rubbing block 23 is attached to lever 34 by rivets 39, and the leg 24 cooperates with cam 40 attached to shaft 41 to cause the movement of lever 34 to separate contact 35 from contact 36. A spring 42 having one 100 end engaging lever 34 and the other end coiled around a stud 43 and its intermediate portion coiled around the hub 33, causes the block 23 to engage the cam or the contact 35 to engage the contact 36. Due to the action 105 of cam 40, the leg 24 of block 23 is subjected to bending stress which is greatest at the apex of the angle formed by the legs.

This bending action is resisted by the large number of warp threads which continue from one leg into the other. The action of the cam subjects the end face of leg 24 to wear, which is resisted to a large extent due to the presence of the relatively large number of warp threads which terminate in the end face of the leg 24.

While the form of embodiment of the 10 present invention as herein disclosed, constitutes a preferred form, it is to be understood that other forms might be adopted, all coming within the scope of the claims which follow.

15 What is claimed is as follows:

1. A cam rubbing block having angularly disposed legs and including a plurality of layers of cloth which extend into both legs, the warp threads of the cloth extending sub-

stantially parallel to the side faces of the 20 legs.

2. A cam rubbing block having angularly disposed legs and including a plurality of layers of cloth which extend into both legs, the warp threads of the cloth extending substantially parallel to the side faces of the 25 legs, and terminating in the end faces of the legs.

3. A cam rubbing block having angularly disposed legs and including a plurality of 30 layers of woven cloth which extend throughout both legs, one set of threads of the cloth extending substantially perpendicular to the end faces of the legs.

In testimony whereof I hereto affix my 35 signature.

FREDERICK C. KROEGER.
